CLAIM

I claim the ornamental design for a bottle, as shown and described.

DESCRIPTION

FIG. 1 is a front top perspective view of the bottle showing our new design;

FIG. 2 is a rear bottom perspective view thereof;

FIG. 3 is a front elevation view with the right side, left side and rear elevation views being identical;

FIG. 4 is a top view thereof; and,

FIG. 5 is a bottom view thereof.

The broken lines in the drawings depict environmental subject matter only and form no part of the claimed design.
